RELEASING TUBE ADAPTER FOR SUPPORTING TUBES OR THE LIKE

George B. Markle, Jr., Hazleton, Pa., assignor to
Freeland Spool and Bobbin Corp., Hazleton, Pa.,
a corporation of Pennsylvania

Application March 23, 1943, Serial No. 480,159.

7 Claims. (Cl. 242—72)

This invention relates to certain new and useful improvements in a releasing tube adapter for supporting tubes or the like, the object being to provide an adapter with a plurality of spring actuated members for engaging the inner wall of a tube or the like for locking the tube thereon so that it will rotate therewith; the member being provided with projecting fingers having inclined faces adapted to be engaged by a ring-like releasing member for compressing the gripping members to allow the tube to be readily removed from the adapter.

Another object of my invention is to provide a releasing tube adapter which is exceedingly simple and cheap in construction, the gripping members being so mounted that a very strong and durable adapter is produced.

Another object of my invention is to provide an adapter composed of a very few parts which are so mounted that they can be easily assembled, means being provided for limiting the outward movement of the members for engaging the tube.

In the drawing:

Fig. 1 is a longitudinal section partly in elevation of an adapter constructed in accordance with my invention showing a tube in position thereon.

Fig. 2 is a transverse section.

Fig. 3 is an end view of the adapter.

Fig. 4 is a side elevation of a modified form of blade.

In carrying out my invention I employ a barrel A having a projection C at each end provided with gudgeon pins D on which the adapter revolves. The barrel is provided with a plurality of longitudinally disposed grooves E the bottoms of which are formed with inclined portions as clearly shown. Arranged in the grooves are blades F having inclined inner edges, the point of contact of the blade with the inclined bottom of the groove forming a fulcrum G upon which the blade rests and moves as the blade expands and contracts as a tube is placed on or taken off the adapter. Each blade F has a groove H formed in its outer edge in which is arranged a strip of friction producing material I having beveled ends as shown, to facilitate the placing of the tube on the adapter as the blades are compressed as the tube rides up the inclined end of the material. The under edges of the blades are provided with bores J and the bottom of the grooves E are provided with bores K in which are disposed coil springs L for forcing the blades outwardly to frictionally engage the tube. Pins M are carried by the under edges of the blades working in

10 sockets N formed in the bottom of the grooves E for preventing longitudinal movement of the blades in the grooves of the barrel.

Discs O and P are secured to the ends of the barrel A provided with slots O' and P' registering with the grooves E of the barrel for holding the blades in position and for limiting the outward movement of the blades. A head Q is secured to one end of the barrel over the disc P to provide a stop for the tube when being placed thereon as shown in Fig. 1.

15 The blades F are formed with tapering fingers F' at one end providing inclined faces adapted to be engaged by a ring like releasing member as disclosed in my Patent No. 2,294,677 for compressing the blades to release the tube from the adapter.

20 In the modification shown in Fig. 4, the blade R is provided with a serrated edge for engaging the tube.

I claim:

1. A releasing tube adapter comprising a barrel having a plurality of grooves, spring-actuated blades mounted in said grooves, the outer faces of said blades being provided with grooves to receive friction producing material, means for preventing longitudinal movement of said blades in said grooves, discs carried by the barrel for limiting the outward movement of said blades in said grooves, said blades being provided with tapering fingers adapted to be engaged by a ring tube releasing member.

2. A releasing tube adapter comprising a barrel having a plurality of grooves, spring-actuated blades mounted in said grooves, the outer faces of said blades being provided with serrated edges, means for preventing longitudinal movement of said blades in said grooves, means carried by the barrel for limiting the outward movement of said blades in said grooves, said blades being provided with tapering fingers adapted to be engaged by a ring tube releasing member.

3. A releasing tube adapter comprising a barrel having gudgeons at its ends, a plurality of longitudinally disposed grooves formed in said barrel having bottoms with inclined portions, blades mounted in said grooves having inclined under edges, the point of contact between said blades and the inclined portions of said grooves forming a fulcrum upon which said blades rock, springs for forcing said blades outwardly, discs secured to the ends of said barrel provided with slots to receive the ends of blades for limiting the outward movement of said blades, means carried by one end of the barrel forming a stop

for a tube when placed on said barrel, said blades being provided with tapering fingers adapted to be engaged by a releasing ring for compressing said blades to release said tube.

4. A releasing tube adapter having gudgeons at its ends, comprising a barrel provided with a plurality of longitudinally disposed grooves having bottoms with inclined portions at an angle to the axis of the barrel, spring actuated blades normally held in expanded position mounted in said grooves on said inclined portions and adapted to engage a tube or the like, means for limiting the outward movement of said blades, said blades being provided with tapering fingers adapted to be engaged by a ring like releasing member for compressing said blades to release the tube or the like.

5. A releasing tube adapter comprising a barrel, a plurality of rocking blades mounted in said barrel, resilient yielding means for normally forcing said blades outwardly to engage the inner wall of a tube when placed on said barrel, means for limiting the outward movement of said blades, said blades being provided with fingers at one

end extending outwardly beyond the end of the barrel and adapted to be engaged by a separate releasing member for compressing said blades for releasing said tube.

6. A releasing tube adapter comprising a barrel, a plurality of resiliently supported expandible blades mounted in said barrel normally held in expanded position for engaging the inner wall of a tube, means for limiting the outward movement of said blades, said blades being provided with fingers extending outward beyond the barrel at one end having inclined faces adapted to be engaged by a releasing member for compressing said blades for releasing the tube.

7. A releasing tube adapter comprising a barrel provided with a plurality of spring actuated expandible blades normally held in expanded position adapted to engage a tube when placed thereon, said blades being provided with tapering fingers at one end extending outwardly beyond the barrel and adapted to be engaged by a ring-like releasing member for compressing said blades to release said tube.
